UNITED STATES PATENT OFFICE.

CYRUS F. BAKE, OF FULLERTON, NEBRASKA.

CAR-COUPLING.

SPECIFICATION forming part of Letters Patent No. 554,970, dated February 18, 1896.

Application filed November 30, 1895. Serial No. 570,718. (No model.)

To all whom it may concern:

Be it known that I, CYRUS F. BAKE, a citizen of the United States of America, residing at Fullerton, in the county of Nance and State 5 of Nebraska, have invented certain new and useful Improvements in Car-Couplings; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 The object of this invention is to provide an improved car-coupling and means for holding the locking-bar out of an operative position; and it consists in the construction and combination of the parts, as will be herein- 20 after fully set forth and particularly pointed out in the claims.

In the accompanying drawings, forming part of this specification, Figure 1 is a vertical sectional view of a car-coupling constructed in accordance with my invention. Fig. 2 is a plan view of the draw-bar and coupling-head and parts to which they are connected, the coupling-head being partly in section. Fig. 3 is a detail perspective view of the means 25 for holding the locking-bar out of an operative position. Fig. 4 is a plan view of Fig. 3, and Fig. 5 is a plan view of the coupling-link.

A designates the coupling-head and B the draw-bar which passes through a central longitudinal aperture in the coupling-head and is attached thereto by a transverse pin b, the forward end of the draw-bar being formed into a head, which lies in a corresponding recess in the coupling-head. The coupling-head A is preferably made of a casting shaped 35 so that the sides converge rearward, as shown in Fig. 2. The draw-bar and coupling-head are attached to the car by means of longitudinal beams C and C', which are secured 40 to the under side of the car, to be substantially parallel with the sides of the coupling-head and a slight distance therefrom. The beams are connected to each other by cross-pieces c c, c', and c'', the cross-pieces c c lying 45 in recesses in the upper and lower sides of the coupling-head, while the cross-piece c' has an aperture through which the rear end of

the draw-bar passes, and the forward end of the coupling-head rests upon the cross-piece c''. Encircling the draw-bar and interposed between the cross-piece c' and the rear end of the coupling-head A is a helical spring C'', the tendency of which is to force the coupling-head forward, the movement in both directions being limited by the length of the 55 recesses a a hereinbefore referred to. It will also be noted that an excessive rearward movement of the coupling-head would be prevented by its jamming between the beams C and C', the arrangement of said beams providing for this.

The link-chamber of the coupling-head tapers rearward, as shown in Fig. 2, and in the upper wall of the same is formed a recess in which the locking-bar D is pivoted, the forward end of the recess forming a shoulder a', against which the shoulder a'' at the forward end of the locking-bar bears when its free end is engaged by the coupling-link. To the free end of the locking-bar is connected a 70 link d, which extends through an aperture a''' in the upper part of the coupling-head and is connected to the device hereinafter described for raising the locking-bar and holding it in a raised position. The forward end 75 of the coupling-head is provided with vertical apertures to receive the ordinary coupling-pin.

E designates a casing or housing, which is provided at its lower end with outwardly-projecting flanges e, by means of which it is secured to the top of the car, and within this casing or housing is pivoted a block F, said block being preferably of metal, to give it weight, and is in the form of a segment, as 85 shown in Fig. 1, the pivot-pin f passing through the same adjacent to the angle thereon. To the forward end of the segment or block F is attached a chain or flexible connection f', said chain being also attached to a vertical rod d', 90 which is connected at its lower end to the link d, extending from the locking-bar D. The rod d' is guided in suitable links or eyes attached to the forward end of the car, and the lower end of the same is bent outward, as 95 100 shown, to engage the link d.

The rear end of the upper part of the casing or housing E is cut away, as shown in Fig. 4, to provide for the movement of a lever

F', which is secured to the rear end of the segment or block F and provides a means for operating the same to raise the locking-bar D. To hold the locking-bar in a raised position 5 or out of operation the casing E is provided with a gravity-catch G, which is pivoted between apertured ears e' e' thereon and has a projection g, which passes through an aperture in the casing and engages an aperture 10 f² in the segment or block. The outer end of the catch is weighted to cause the projection g to automatically engage the aperture in the segment or block, and in order to operate said catch from the side of the car I attach 15 a flexible connection or cord g' thereto and lead said cord to a suitable point at one side of the car.

The device herein shown and described is an improvement upon my previous patent, 20 No. 160,294, dated March 2, 1875.

The operation of the parts will be readily understood from the drawings and foregoing description, the coupling of the cars being automatic when the locking-bar D is lowered, as 25 shown in Fig. 1, for in this position the link H, when it passes into the coupling-head, will raise the locking-bar, and the latter passing over the head h of the link will fall into position to engage the shoulder h' thereof, the 30 jar occasioned by the coupling-heads coming together being taken up by the helical spring C², and when the train is being drawn forward the pivot-pin of the locking-bar will be relieved of strain by the shoulder a' on the 35 upper part of the link-chamber. When it is desired that the cars should not couple when they come together the locking-bar D may be held out of an operative position by swinging the segment or block F back until the aperture f² therein is engaged by the gravity- 40 catch G.

Having thus described my invention, what I claim as new, and desire to secure by Letters Patent, is—

45 1. The combination in a car-coupling, of a coupling-head shaped to present side walls

which converge rearward, a draw-bar passed through a central longitudinal aperture in the coupling-head and having a head which lies in a corresponding recess in said coupling-head, 50 the draw-bar being secured to the coupling-head by a transverse pin; together with longitudinal bars or beams C and C' converging rearward and having cross-pieces c c, c', and c² rigidly secured thereto with which the draw-bar and coupling-head engage, and a helical spring encircling the draw-bar and interposed between the cross-piece c' and the coupling-head, the coupling-head being recessed to receive the cross-pieces c c, substantially as 60 shown and for the purpose set forth.

2. In a car-coupling, the combination with the coupling-head having a shouldered locking-bar pivoted therein, of a segment or block F pivoted within a casing and having an aperture or notch in one side of the same, and a gravity-catch pivoted on one side of the casing and having a projection which engages the aperture or notch in the segment, the segment being connected to the locking-bar, substantially as shown and for the purpose set forth.

3. In a car-coupling, the combination with the coupling-head having a locking-bar pivoted therein, of a casing or housing E secured 75 on top of the car, a segment F pivoted in said casing or housing and provided at its rear end with an operating-lever F', a gravity-latch G pivoted on one side of the casing and provided with a projection g adapted to engage a notch 80 or aperture in the segment, and a cord extending from the gravity-latch to a point at one side of the car, the segment being connected to the locking-bar by a flexible connection f', rod d' and link d, substantially as 85 shown and for the purpose set forth.

In testimony whereof I affix my signature in presence of two witnesses.

CYRUS F. BAKE.
